UNITED STATES PATENT OFFICE.

CHARLES TUTEUR, OF NEW YORK, N. Y., ASSIGNOR OF ONE-THIRD TO SAMUEL KAHN,
OF NEW YORK, N. Y.

DESIGN FOR A PULLEY-CASING.

42,720.

Specification for Design.

Patented July 2, 1912.

Application filed March 19, 1912. Serial No. 684,818. Term of patent 14 years.

To all whom it may concern:

Be it known that I, CHARLES TUTEUR, a subject of the King of Great Britain, at present residing in the city of New York, borough of Manhattan, in the county and State of New York, have invented a new, original, and ornamental Design for a Pulley-Casing, of which the following is a specification, reference being had to the accompanying drawing, forming a part there-

of, in which the figure is a perspective view showing my new design.

I claim—

The ornamental design for a pulley casing, as shown.

CHARLES TUTEUR.

Witnesses:

J. L. McAULIFFE,
JOHN P. DAVIS.
